CLAIM

The ornamental design for a spray head holder, as shown and described.

DESCRIPTION

FIG. 1 is a perspective view of a spray head holder according to our new design;

FIG. 2 is a front elevational view thereof;

FIG. 3 is a left side elevational view thereof (a right side elevational view being a mirror image thereof);

FIG. 4 is a top plan view thereof;

FIG. 5 is a bottom plan view thereof; and,

FIG. 6 is a rear elevational view thereof.

The broken line is for illustrative purposes and forms no part of the claimed design.
